IMPLEMENT HANDLE

William Steinen, South Orange, N. J.

Application October 27, 1938, Serial No. 237,311

6 Claims. (Cl. 306—38)

The present invention relates to an implement handle and particularly relates to a handle which may be utilized in connection with toilet or vanity sets for carrying articles, such as shoe horns, button hooks, nail files, cuticle knives, and so forth.

It is among the objects of the present invention to provide a simple inexpensive implement handle of the character above described which may be readily and inexpensively stamped out of sheet metal materials and which, at the same time, may be readily adjusted firmly to receive any one of the various instruments above described and which may be utilized in connection with a dresser and toilet set.

Other objects will be obvious or will be apparent during the course of the following specification.

In accomplishing the above objects, it has been found most satisfactory, according to one embodiment of the present invention to provide a continuous channel-shaped rim member, the split ends of which rim are turned inwardly and held in position by a cap which cap may fit upon an elongated rod extending from the particular implement which it is desired to use.

The handle may receive filler or spacer members which are received in the channel member and are held together by said channel member and which, at the same time, properly space and position the legs of said channel member.

By providing an opening in the base of the continuous channel member, it is possible to insert a gripping device, such as a nut or sleeve which may be threaded onto the threaded end of the rod extension of the implement and draw the entire construction up tightly together.

The above and other objects will appear more clearly from the following detailed description when taken in connection with the accompanying drawing, and will illustrate a preferred embodiment of the inventive idea.

In the drawing:

Figure 1 is a front view of a typical implement handle with a shoe horn being shown as the illustrative element, this figure being somewhat larger than full size;

Figure 2 is an end view upon the line 2—2 of Figure 1;

Figure 3 is a transverse sectional view upon the line 3—3 of Figure 2 with the end of the shoe horn being broken away;

Figure 4 is a transverse sectional view through the handle on the line 4—4 of Figure 3 upon enlarged scale as compared to Figure 3; and

Figure 5 is a front view of an alternative implement construction upon a somewhat smaller scale as compared to Figure 1.

Referring to Figures 1 to 4, the implement B, illustratively a shoe horn, is provided with a handle A to which the invention is most particularly directed.

In lieu of a shoe horn, it is also possible to use cuticle pushers, cuticle knives, nail files and also to a lesser degree, hair brushes, mirrors, combs, and so forth.

As best indicated, the shoe horn B is provided with a head member 10 which receives the rod 11, said rod being extended through the handle A. The rod 11 has a threaded portion 12 which receives the bushing, nut or cap 13 having the tapped recess 14.

The handle itself is composed of the channel member 15, bent in the form of a U, as shown best in Figures 1 and 3. The legs 16 of the U have the inwardly bent flanges 17 at the end of the handle.

The side flanges 18 extend the full length of the channel member 15 to terminate short of the inwardly bent portions 17 and they fit into the recesses 19 in the handle plates 20.

The handle plates 20 are provided with the edge flange portions 21 which abut at 22 and which are received inside of the channel member 15 and abut the base 23 of said channel member 15.

The plates 20 in the construction shown are also provided with a second step or shoulder member 24 which is flush with the flanges 18 and with a middle member 25 which projects beyond the flanges 18 as best shown in Figure 4.

The ends of the plates 20 are turned inwardly to form the flanges 26 which abut at 27.

The end flanges 26 are provided with the opening 28 which receives the tapped shank of the cap 13, said shank also extending through the opening 29 in the base 30 of the channel member 15.

The cap 31 has the shoulders 32 which abut the flanges 17 of the channel member 15. The flanges 17 in turn rest against the inturned portions 26a of the plates 20 as shown in Figure 3.

Beyond the shoulders 32 are the flanges 33 which closely contact and grip the end portions of the plates 20 and the end portions of the legs 16 of the channel member 15.

The base of the cap is provided with an opening 34 through which projects the rod 11 and the periphery of which contacts the member 10.

In assembly, the cap 31 is positioned upon the 55

rod 11 and the channel member 15 is placed upon the plates 20, and the plates 20 are then placed upon the rod 11 and the nut or cap 13 is inserted and tightened.

5 The flange 35 of the nut 13 will press against the periphery of the opening 29 drawing the entire construction up and forming a strong unitary construction.

To dismantle or replace the implement B, the 10 cap 13 may be loosened whereupon the implement B with the rod 11 may be removed and a new implement inserted.

15 It is apparent the specific illustrations shown above have been given by way of illustration and not by way of limitation and that the structures above described are subject to wide variation and modification without departing from the scope or intent of the invention, all of which variations and modifications are to be included within the 20 scope of the present invention.

What is claimed is:

1. An implement handle, comprising a central rod carrying the implement at one end, and being threaded at the other end, two elongated side 25 plates enclosing said rod, a channel member engaging and receiving the edges of said plates, having split ends at the end of the rod adjacent the implement, a cap adjacent said implement enclosing said split ends, and a nut engaging said threaded end and drawing up said cap and implement on said plates and channel member.

30 2. An implement handle, comprising a central rod carrying the implement at one end, and being threaded at the other end, two elongated side plates enclosing said rod, a channel member engaging and receiving the edges of said plates, having split ends at the end of the rod adjacent the implement, a cap adjacent said implement enclosing said split ends, and a nut engaging said threaded end and drawing up said cap and implement on said plates and channel member, said channel member being provided with flanges and the edges of said plates being provided with recesses to receive said flanges.

35 3. An implement handle, comprising a central rod carrying the implement at one end, and being threaded at the other end, two elongated side

plates enclosing said rod, a channel member engaging and receiving the edges of said plates, having split ends at the end of the rod adjacent the implement, a cap adjacent said implement enclosing said split ends, and a nut engaging said 5 threaded end and drawing up said cap and implement on said plates and channel member, said plates being provided with inturned flanges and said flanges abutting each other inside of said channel members.

10 4. An implement handle, comprising a central rod carrying the implement at one end, and being threaded at the other end, two elongated side plates enclosing said rod, a channel member engaging and receiving the edges of said plates, 15 having split ends at the end of the rod adjacent the implement, a cap adjacent said implement enclosing said split ends, and a nut engaging said threaded end and drawing up said cap and implement on said plates and channel member, 20 said channel member being U-shaped and having an opening at the bottom of the U to receive the threaded end of said rod and said nut.

25 5. An implement handle, comprising a central rod carrying the implement at one end, and being threaded at the other end, two elongated side plates enclosing said rod, a channel member engaging and receiving the edges of said plates, having split ends at the end of the rod adjacent the implement, a cap adjacent said implement 30 enclosing said split ends, and a nut engaging said threaded end and drawing up said cap and implement on said plates and channel member, said nut having an elongated tapped shank extending inside of said channel member to receive the 35 threaded end of said rod.

40 6. An implement handle, comprising a central rod carrying the implement at one end, and being threaded at the other end, elongated side plate means enclosing said rod, an abutment member between the ends of the plate means and said implement, an edge member holding said plate means together, and a nut engaging said threaded end and drawing up said abutment member on said side plate means.

45 WILLIAM STEINEN.
